United States Patent Office

Des. 206,337
Patented Nov. 29, 1966

206,337

TOY MOVIE PROJECTOR

Karl A. Utrecht, Cincinnati, Ohio, assignor to Kenner
Products, Cincinnati, Ohio, a corporation of Delaware

Filed Nov. 26, 1965, Ser. No. 88,221

Term of patent 14 years

(Cl. D34—15)

Fig. 1

Fig. 2

FIG. 3

FIG. 4

FIG. 5

FIG. 6

FIGURE 1 is a side elevational view of a toy movie projector showing my new design.

FIGURE 2 is a side elevational view thereof illustrating the appearance of the side opposite that shown in FIGURE 1.

FIGURE 3 is a top plan view thereof.

FIGURE 4 is a front elevational view thereof.

FIGURE 5 is a rear elevational view thereof.

FIGURE 6 is a bottom plan view thereof.

I claim:

The ornamental design for a toy movie projector, substantially as shown.
